Murray Schotland, New York, N. Y.

Application January 15, 1953, Serial No. 23,146

Term of patent 14 years

(Cl. D9—2)

To all whom it may concern:

Be it known that I, Murray Schotland, a citizen of the United States, residing in New York city, in the county of New York and State of New York, have invented a new, original, and ornamental Design for a Combination Toothbrush and Casing Therefor, of which the following is a specification, reference being had to the accompanying drawing, forming part thereof.

Fig. 1 is a front view of combination toothbrush and casing therefor, showing my new design,

Fig. 2 is a side view thereof,

Fig. 3 is a top view thereof in separated form,

Fig. 4 is a side view thereof in separated form, and

Fig. 5 is a perspective view of the combination toothbrush and casing therefor, showing the

toothbrush and casing therefor in combined form, ready for use.

Both side views and the top and bottom views are the same.

I claim:

The ornamental design for a combination toothbrush and casing therefor, substantially as shown, and described.

MURRAY SCHOTLAND.
